UNITED STATES PATENT OFFICE.

FRANK E. MILLER, OF NEW YORK, N. Y.

CUSPIDAL-DIAPHRAGM CONSTRUCTION.

1,294,137.

Specification of Letters Patent. Patented Feb. 11, 1913.

Application filed May 10, 1912. Serial No. 233,774.

To all whom it may concern:

Be it known that I, FRANK E. MILLER, a citizen of the United States, and a resident of New York city, county and State of New York, have invented certain new and useful Improvements in Cuspidal-Diaphragm Constructions set forth in the following specification.

The object of this invention is to facilitate the exact and accurate patterning of the cuspidal diaphragms such as those employed in various of my cusp diaphragm mechanisms, as for example those employed in the structures disclosed in my patent for cusp diaphragm mechanism, No. 1,220,669, patented March 27, 1917. Although for many purposes it is desirable to employ stamping dies for the manufacture of these cuspidal diaphragms by a stamping process out of sheet metal, it is of course first necessary to obtain a pattern to determine the necessary contour for the dies. This invention contemplates primarily the geometrical construction of such a pattern, although it is to be understood that the pattern itself, if made out of suitable material, may itself constitute a satisfactory cuspidal diaphragm.

My invention will better be understood by reference to the following specification, which is directed to the illustrative diagram in the accompanying drawings, which form a part hereof.

On a suitable sheet of material, sheet metal if a working diaphragm is to be produced, or a sheet of paper or bristol board, like the accompanying drawings, if merely a pattern is to be made, is laid out a circular area 10 having the circular circumference 11, and with its center at X. Any point A upon the circumference 11 is selected with a radius AX, being the radius of the circular area. An arc 1 is laid off about A as a center. Then, still with A as a center, and a radius equal to A^{12} or three-fifths of AX, the radius of the circumference, a second arc 2 is struck to intercept the circumference 11 at B. Then, with B as a center and with a radius equal to four-fifths of AX, the radius of the circumference, a third arc 3 is struck to intercept the arc 1 at C. In this manner the point C, to constitute the umbo or apex of the cuspidal diaphragm when completed, is determined. In order to alter the plane sur-

face of the original circular area 10 into a dished configuration, a part of the material 55 of the original circular area must be removed, the edges of the remainder left by the cutout portion brought together, and it is desirable that the periphery of the resulting construction approximate a circle. To these ends I first determine the point D on the circumference 11. The point D is such that the length of the arc BD is one-sixth of the length of the arc BA. At this juncture it may be noted with interest that a triangle ABC, completed by straight lines joining the points A, B and C, for the purpose of locating the umbo C, is the right triangle of Pythagoras, having its sides in the proportion 3:4:5. 70

With the point D located, it should be joined to C with a straight line or what may be termed an eccentric radius. Likewise the point A should be joined by a straight line with the point C, which line may likewise be termed an eccentric radius. An eccentric sector 14, comprising the two-shaded areas between the lines AC, CD, and arc AD, is then demarcated. This eccentric sector is the part of the original circular area 10 to be 80 removed by cutting along the lines AC and DC to cause the remainder of the original area to assume a dished contour. Were nothing else done but the removal of this eccentric sector, it is obvious that the point D 85 would abut the leg AC at the point E, which is determined by striking the arc 15 about C as a center and with CD as a radius. As it is an objective that the rim contour of the finished diaphragm be substantially circular, 90 it is necessary to remove a part of the margin, more at the locality AE than at the locality D, where nothing need be removed. 95

To determine the amount of the rim that should be removed, it is convenient to divide the circular circumference, measured the long way from A to D, into a number N of equal parts. In the present instance N equals 12, which is a suitable number. The eccentric radii CF, CG, CH, CI, CJ, CK, CL, CM, 100 CN, CO, CP are drawn. The line AE represents the amount of rim that should be removed at the locality E, but for other localities along the other eccentric radii the amount becomes gradually less until it is zero 105 at the point D. A convenient manner of de-

termining the points F', G', H', I', J', K', L', M', N', O' and P' is to employ the formula

$$\frac{N-1}{N} \quad \dots \quad \frac{N-N}{N}$$

for the lengths of the lines FF', GG', etc., down to the point D, where this length is zero, given by the last of the series $\frac{N-N}{N}$.

10 A convenient geometrical method of applying this formula is to project the initial length AE upon the line A'E' where, by proportional parts, it may be divided into N equal divisions Q, from which the desired lengths FF', GG', etc., may be measured off along the eccentric radii. The points E', F', G' down to the point D should be joined by a smooth curve R, which is the pattern for the 15 rim of a finished cusp. When the edges EC and DC are brought together, the points E and D coincide and the smooth curve R assumes the form of substantially a perfect 20 circle and is the complete rim of the eccentrically dished diaphragm thus patterned.

25 Although I have described in detail a preferred method of patterning a cuspidal diaphragm, I appreciate the fact that there are many steps therein individually novel and it is so contemplated in the claims. It is also to be understood that the laying out method set forth in the claims is by no means of necessity limited to the laying out 30 of each diaphragm to be made, but is intended to cover the laying out of a master diaphragm or pattern diaphragm from which duplicates or copies may be made.

35 What I claim and what I desire to secure by United States Letters Patent is:—

40 1. The method of laying out a cuspidal diaphragm comprising, laying out a circular figure; selecting an eccentric point in the neighborhood of the center of said figure; with said eccentric point as an apex 45 cutting out an acute-angular sector from said circular figure, the place of section being so selected that one straight edge of the sector will be longer than the other, the corresponding edges of the larger sector being similarly unequal; laying off a distance 50 from said apex along the longer leg of said larger sector equal to the length of the shorter leg of said sector; and trimming the rim of said larger sector a regularly 55 decreasing amount from the distance laid off on the longer leg of said sector to the outer end of said shorter leg.

60 2. The method of laying out a cuspidal diaphragm comprising, laying out a circular figure; from any point A on the circumference of said circular figure striking an interior arc 1 of a radius equal to the

radius of said figure; with A as a center intersecting the circumference of said figure at B with arc 2 of radius $\frac{1}{2}$ of the radius of said figure; and with B as a center and radius $\frac{1}{2}$ initial radius causing arc 3 to intersect arc 1 at C, to indicate the umbo or apex of the desired cuspidal diaphragm.

65 3. The method of laying out a cuspidal diaphragm comprising, laying out a circular figure; from any point A on the circumference of said circular figure, striking an interior arc 1 of a radius equal to the radius of said figure; with A as a center intersecting the circumference of said figure at B with arc 2 of radius $\frac{1}{2}$ of the radius of said figure; with B as a center and radius $\frac{1}{2}$ initial radius causing arc 3 to intersect arc 1 at C, to indicate the umbo or apex 70 of the desired cuspidal diaphragm; laying off $\frac{1}{2}$ of the arc BA from B to D; and removing figure ACD.

75 4. The method of laying out a cuspidal diaphragm comprising, laying out a circular figure; from any point A on the circumference of said circular figure, striking an interior arc 1 of a radius equal to the radius of said figure; with A as a center intersecting the circumference of said figure at B with arc 2 of radius $\frac{1}{2}$ of the radius of said figure; with B as a center and radius $\frac{1}{2}$ initial radius causing arc 3 to intersect arc 1 at C, to indicate the umbo or apex 80 of the desired cuspidal diaphragm; laying off $\frac{1}{2}$ of the arc BA from B to D; and removing figure ACD; marking E on AC so that CE equals CD; and trimming the margin of the remainder of said circular figure a gradually decreasing amount varying AE 100 at E to nothing at D.

85 5. In the marginal trimming of a cuspidal diaphragm pattern, dividing the circumference of a circular figure from which an eccentric sector has been removed into N equal arcs; connecting the apex of said sector with the ends of said arcs with eccentric radii; from the long leg of said eccentric sector marking off the difference 90 between the length of said long leg and the length of said short leg; from the remaining eccentric radii marking off respectively 95 105 110 115

$$\frac{N-1}{N}, \frac{N-2}{N} \dots \frac{N-N}{N}$$

times said difference in length; and connecting the end of said short leg by a smooth curve with each of the points on said radii so marked off.

120 In testimony whereof I have signed my name to this specification, this 16th day of February, 1918.

FRANK E. MILLER.
